ATTORNEY

UNITED STATES PATENT OFFICE.

HENRY SPENGLER, OF NEW YORK, N. Y.

CLOSURE.

Application filed November 23, 1922. Serial No. 602,721.

To all whom it may concern:

Be it known that I, HENRY SPENGLER, a citizen of the United States, residing at New York, in the county of New York and State of New York, have invented certain new and useful Improvements in Closures, of which the following is a specification.

This invention relates generally to container caps or closure members and more particularly relates to an improvement on the general type of closure member shown in my United States Patent No. 1,074,907 in which a resilient and bulged central area may be depressed to produce a spreading and releasing movement of marginally arranged container gripping members and thus remove the closure member without the use of a tool.

The type of closure member thus described has gone into extensive use and has satisfactorily performed its function. I have found, however, in the course of further experiments that a closure member of the same general type can be provided which will embody improved features including a greater spread or extent of opening of the gripping members in the releasing position, a greater leverage resulting in greater ease of manipulation, an operating movement of the bulged closure portion which takes place in a series of progressive stages rather than in a single snap movement, and the use of relatively thin and inexpensive metal from which to form the closure member.

I have found that it is possible to obtain a greater range of radial action while retaining easy actuation by making the bulge of the disk portion nonuniform in zones or areas, thus apparently establishing lines or zones of natural circular flexure. The resulting curvature either in the bulged and closed or indented and open aspects or condition of the closure is also nonuniform.

I find, for example, that by stamping circular concentric zones so as to slightly work and compress the material there seems to result a slight thinning of the material giving to such zones a higher elasticity and a different curvature, which may advantageously be reverse in successive zones. The total bulge may in such a case be considerable, but the action much easier than if the same bulge were formed with uniform cur-

vature and elasticity. Also the radial throw seems to be greater than would be produced by the same total bulge with uniform curvature, or what is the same thing, a greater throw seems to result from a given bulge.

The invention includes the thinning and accompanying expansion in its own plane of the sheet metal forming the cap with a resulting warping or bulging of the closure member in a plurality or multiplicity of areas between the center and the lateral boundaries thereof. The locally warped bulged areas may conveniently take the form of annular zones or areas connected by ridges whose accumulative expansive effect produces a pronounced bulge or dome in the otherwise flat face of the closure member. I find that the production of the bulge or dome in a series of steps or stages gives very beneficial results in that the metal is rendered advantageously resilient and can be manipulated by moderate pressure which is progressively distributed in successive stages from the central portion of the cap to the boundaries thereof. The movement of the bulged portion of the cap from one side to the other of the normal central plane causes a pronounced radially directed expanding or contracting movement of a set of gripping fingers or members extending outwardly in a substantially perpendicular relation to one face of the cap member along the margin thereof.

Many specifically different modes or arrangements of this nonuniform working of the metal may be used with good results. I show one form which I have found to work well which illustrates the combined effects of differential working so that there are concentric zones of different curvature, thickness and elasticity.

Such a cover seems to have a double buckling action which apparently accounts for the ease of action of a cap so considerably bulged. This is not noticeable in ordinary usage, but by slowly operating it two sharply marked stages of action distinguished by different pitched sounds are observable.

I am unable to give any precise scientific statement of what takes place, but the result of the nonuniform zoning is to produce a cap of markedly greater radial throw for a given ease of action and extent of bulge,

thus rendering it especially adapted for large covers and for packages having large or variable locking shoulders.

In the drawings in which a number of 5 embodiments of the invention have been selected for illustration,

Figure 1 is a view in side elevation of a closure cap member embodying the invention.

10 Figure 2 is a view in vertical section of the cap member shown in Figure 1.

Figure 3 is a view similar to Figure 2 showing the cap member in releasing position.

15 Figure 4 is a plan view of the cap member shown in Figure 1.

Figure 5 is a plan view of a modified form of cap member embodying the invention.

20 Figure 6 is a view in section of still another form of cap member embodying the invention.

Referring to the drawings for a more detailed description of the invention, a closure 25 member is shown at 5 which is adapted to close the mouth of a wide-mouthed container 6 such as is used for holding shoe paste or dressing. The closure member or cap 5 has a bulged or dome-shaped formation as indicated in Figures 1 and 2 and is sufficiently 30 resilient to permit of the bending or buckling of the bulged portion through a plane coincident with the base of the dome portion as indicated in Figure 3.

35 In order to obtain a sufficient extent of movement of the dome-shaped portion of the cap member to produce a proportionate and desirable spreading or gripping action of the container-gripping member 7 to cause 40 the fingers either to release their hold on the rim or bead 8 on the container 6 or to move inwardly into gripping relation with the bead, I have provided the flat body portion of the closure member with a plurality of 45 areas that have been subjected to operations designed to reduce the thickness of the metal and at the same time expand the metal laterally within its own plane. It will 50 be clear that the expansion of the metal laterally increases its superficial area and produces a bulged or bowed formation of the face of the cap. The accompanying thinning of the metal increases its resiliency while the changes of curvature even though 55 slight seem to reduce the excessive rigidity and stiffness that otherwise inheres in the bowed or arched formation.

I find that the expansion and thinning of the metal in a multiplicity of areas facilitates the bending or buckling of the cap to cause it to grip or release the container. With this construction a moderate pressure applied to the bulged area at a central or other point results in a variably localized 65 distribution of the bending or buckling ac-

tion that is effective to produce the relatively extensive movement required with the exertion of only a moderate degree of force. The buckling of the cap member from the outwardly bulged position such as is indicated in Figure 2 of the drawing to the inwardly bulged condition shown in Figure 3 results in a corresponding swing of the gripping flange members 7 from their gripping to their releasing position. It will be seen that the relatively extensive movement of the bulged or crowned portion of the cap produces an extensive inward or outward swinging movement of the gripping members 7 about the juncture points of the gripping members with the margin of the bulged portion.

In producing the expanded area of metal to provide the bulged or crowned portion the metal forming the cap is compressed or stamped between metal working members that act to consolidate the metal, in a plurality of local areas. The change thus produced increases the elasticity and resiliency of the metal to an extent sufficient to insure the ready accomplishment of the buckling operation. The spreading or lateral expanding effect that is produced in the metal when the thickness is reduced increases the superficial area of the locally expanded regions and produces a bulge or dome-shaped formation of the cap as a whole.

I find that the production of a bulge or crown in the cap made up of a multiplicity of differently worked areas and a resulting non-uniform zoning results in an efficient and readily operable closure member that is particularly well adapted for use with containers having relatively wide mouths. In addition the working of the metal that is effected produces a toughening and strengthening effect that is turned to useful account in the use of metal of thinner gage and of relatively less cost than would be otherwise used.

In producing cap members embodying the invention I may so form the bulged portions as to cause them to automatically resume their outwardly bulged position when depressed, or to retain their inwardly bulged position until released by inward pressure exerted on the gripping members, as circumstances may require.

The differently worked portions may take the form of concentrically arranged annular areas 11 as indicated in Figure 4 or they may be formed by peening or stamping operations in spots or relatively small areas 9 as indicated in Figure 5. I contemplate also the use of corrugated dome portions 10 as shown in Figure 6 of the drawings. Other arrangements and dispositions of the worked local areas may be provided.

What I claim is:—

1. A spring closure having a non-uni-

formly resilient central portion and depending separate engaging fingers actuated to locking position by change of curvature of said central portion, and said central portion having regions concentric therewith of different thicknesses extending to the finger portion to produce different resilient action.

2. A snap cover having a bulged non-planar central circular portion and depending edge portions formed as separated engaging fingers, said central circular portion having interrupted zones of varying thicknesses to produce non-uniformly resilient action.

3. A snap cover having a bulged non-planar central circular portion and depending edge portions formed as separated engaging fingers, said central circular portion having concentric interrupted zones of varying thicknesses to produce non-uniformly resilient action.

4. A snap cover having a bulged non-planar central circular portion and depending edge portions formed as separated engaging fingers, said central circular portion having reversely curved interrupted zones of varying thickness to produce non-uniformly resilient action.

5. A snap cover having a bulged non-planar central circular portion and depending edge portions formed as separated engaging fingers, said central circular portion having areas of different thicknesses to produce non-uniformly resilient zones of different elastic properties.

6. A snap cover having a bulged central portion and depending separated circumferential engaging fingers actuated to locking position by change of curvature of said central portion and means for increasing the throw of said locking fingers comprising a plurality of zones of varying thicknesses to produce regions of different resilient action.

7. A snap cover having a bulged central portion and depending separated circumferential engaging fingers actuated to locking position by change of curvature of said central portion and means for increasing the throw of said locking fingers comprising a plurality of concentric zones of varying thicknesses to produce regions of different resilient action.

8. A snap cover having a bulged central portion and depending separated circumferential engaging fingers actuated to locking position by change of curvature of said central portion and means for reducing the force required to operate said cover comprising a plurality of concentric zones of non-uniform thickness.

9. A container closure cap having a resilient bulged formation, and container gripping members carried by the cap and adapted to be moved to gripping or releasing po-

sition by movement of the resilient bulged portion to outward or inward position, said bulged portion of the cap being formed by a plurality of worked areas of different thicknesses.

10. A container closure cap having a resilient bulged formation, and container gripping members carried by the cap and adapted to be moved to gripping or releasing position by movement of the resilient bulged portion to outward or inward position, said bulged portion of the cap being formed by a plurality of locally distorted areas of different thicknesses.

11. A container closure cap having a resilient bulged formation, and container gripping members carried by the cap and adapted to be moved to gripping or releasing position by movement of the resilient bulged portion to outward or inward position, said bulged portion of the cap being formed by a plurality of thinned and laterally expanded areas.

12. A container closure cap having a bulged formation adapted to be buckled to one side or the other of a base plane, and container gripping members carried by the cap and adapted to be moved to gripping or releasing position by the movement of the bulged portion to its outward or its inward position respectively, said bulged portion being formed by a plurality of radially distributed thinned and superficially expanded areas whereby to provide a progressively yielding action when pressure is applied to the bulged portion.

13. A container closure cap having integrally formed container gripping members projecting substantially perpendicularly from the margin of one face thereof, the body portion of said cap member being provided with a series of concentrically arranged annular thinned and laterally expanded areas whereby to produce a flexible and resilient bulged formation, said bulged portion being adapted to be buckled to either side of the base plane whereby to swing said marginally arranged gripping members radially inward or outward to gripping or releasing position.

14. A container closure cap having integrally formed container gripping members projecting substantially perpendicularly from the margin of one face thereof, the body portion of said cap member being provided with a series of radially and annularly distributed thinned and laterally expanded areas whereby to produce a flexible and resilient bulged formation, said bulged portion being adapted to be buckled to either side of the base plane whereby to swing said marginally arranged gripping members radially inward or outward to gripping or releasing position.

15. A container closure cap having in-

tegrally formed container gripping members projecting substantially perpendicular-
ly from the margin of one face thereof, the
body portion of said cap member being pro-
vided with a multiplicity of radially dis-
tributed spot-like areas in which the ma-
terial forming the cap is thinned and later-
ally expanded to produce a resilient bulged
formation, said bulged portion adapted to

yield under pressure to produce a progres- 10
sively acting reversal of its position to
thereby swing the gripping members in-
wardly or outwardly to gripping or re-
leasing position.

In testimony whereof I affix my signa- 15
ture.

HENRY SPENGLER.
